ROTARY MANICURING INSTRUMENT

Merrill Kessler, Oakland, Calif., assignor to
Aristocrat Manicuring Company, a corpora-
tion of Nevada

Application August 21, 1948, Serial No. 45,472

2 Claims. (Cl. 132—75.8)

1

The invention relates to rotary manicuring instruments adapted for power driven operation, as for example at the end of a flexible drive arranged for manual engagement and manipulation by the manicurist.

An object of the present invention is to provide a rotary power driven manicuring instrument of the character described, which is designed for filing of the edge portions of a finger nail to be manicured and which will afford a rapid and precise trimming of the nail with complete safety to the operator and to the person whose nails are being manicured.

Another object of the invention is to provide a rotary manicuring file of the character above which is designed as a companion instrument for use with a power driven manicuring device disclosed in my co-pending application Serial No. 33,077, filed June 15, 1948, and when so used will afford a faster, smoother and better-appearing manicuring of a finger nail.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a perspective view of a rotary manicuring file constructed in accordance with the present invention, shown operatively attached to one end of a flexible drive.

Figure 2 is a side elevation of the instrument and drive connection illustrated in Figure 1, and shown on a somewhat enlarged scale and with a portion in cross section.

Figure 3 is a still further enlarged cross-sectional view of part of the rotary file.

Figure 4 is a front elevation of the part of the file illustrated in Figure 3 with a portion in cross section, as indicated by the plane of the line 4—4 of Figure 3.

The manicuring device of the present invention consists of a handle member 6 formed at one end 7 for detachable connection to an end 8 of a flexible drive 9 having an internal torsional drive element 11 terminating in a shaft part 12 journaled for rotation within the end 8 and having at its extremity a flattened drive tongue 13. Journaled for rotation within the member 6, and mounted substantially axially therethrough,

2

is a shaft 14 retained against longitudinal displacement forwardly of the handle by the engagement of annular shoulders 16 and 17 on the shaft 14 and within the internal bearing bore of the handle portion 6 respectively.

Preferably, the end 7 of the hand piece 6 is reduced in diameter and threaded externally for engagement with a threaded interior wall 18 provided at the end 8 of the flexible drive concentric 10 to and spaced from the drive tongue 13. The drive connection is effected by the provision in one end 19 of the shaft part 14 of a cross slot 21 opening to an end of the shaft for receiving the tongue 13 and joining the tongue and shaft for 15 joint rotation upon threading of the end 7 of the hand piece into the attachment 8. Preferably, the outer diameters of the hand piece 6 and attachment 8 of the flexible drive are the same, so as to provide a flush continuous external surface 20 when these members are joined together for engagement in the hand of the operator. If desired and as here shown, portions of the adjoining periphery of the hand piece 6 and attachment 8 may be knurled to facilitate handling.

25 The opposite end 22 of the shaft 14 is extended to the adjacent end 23 of the hand piece 6 and is formed with an internally threaded bore 24 for receipt of a threaded end 26 of an axially extended stem 27 of the manicuring instrument 28, 30 so as to join the stem end 26 and shaft end 22 for joint rotation.

The instrument 28 is formed as an enlarged disc-shaped head at the forward extremity of the stem 27, and, as will be seen from Figures 1 35 and 2, the stem tapers forwardly to the head 28 from a shoulder 29 formed in the forward end of the threaded stem end 26, which is reduced in diameter as illustrated in Figure 2. The hand piece is also preferably tapered forwardly to the 40 end 23 so as to provide thereat a diameter equal to the diameter of the shoulder 29, whereby a continuous tapered surface is provided from the hand piece to the neck 31 at the rear side 32 of the head 28. Preferably the threaded end 26 of 45 the stem is threaded rather tightly in the bore 24 of the shaft 14 so that the manicuring instrument and its hand piece 6 will normally stay in associated relation. Connection and disconnection of the instrument to the flexible drive is accomplished by means of the threaded connection of the end 7 of the hand piece to the end pieces 50 8 of the flexible drive.

The instrument head 28, as will be seen from the drawings, is substantially disc-shaped with the stem part 31 extending substantially centrally

and axially from the rear face 32 of the head. The rear face 32, as well as the front face 33, is substantially planar and circular as viewed in elevation, see Figures 1 and 4, with the planes of these sides substantially perpendicular to the axis of rotation of the member. Formed in the outer periphery of the head is an annular recess 34 having a substantially flat cylindrical base 36 concentric to the axis of the head and positioned inwardly from the outer extremities of the sides 32 and 33. File serrations 37 are formed in the base 36, and preferably and as here shown, these serrations are cut directly into the base so as to provide file teeth extending in an axial direction and arranged in spaced relation around the entire circumference of the base. As will be best seen from Figures 3 and 4, the outer extremity of these teeth is located at the bottom of the recess and within the outer periphery of the head.

The opposite sides of the recess 34 are formed by annular walls 38 and 39 which extend from the front and rear edges of the base 36 in an outward divergent fashion to the outer extremities of the opposite sides 32 and 33 of the head, so as to define thereat thin annular rims 41 and 42. Of considerable importance is the fact that the tapered sides 38 and 39 of the recess are left perfectly smooth, and thus function to properly guide the edge of a nail to be manicured into position upon the file serrations 37 at the base.

The width of the base 36 of the recess is slightly greater than the normal thickness of a finger nail to be filed to thereby confine the nail on the serrations without appreciable movement of the nail across such width, and the outward divergence of the recess increases this width considerably across the rims 41 and 42 so as to readily permit the insertion of the edge of the nail to be manicured into the recess, with the rims 41 and 42 straddling the nail. In placing the periphery of the head against the edge of the nail to be manicured, the nail edge will normally engage one end of the tapered recess walls 38 and 39 and thereby guide the movement of the head into proper engagement with the edge of the nail, that is, with the nail edge squarely positioned against the serrated recess base 36. Also, the location of the file serrations at the base of the recess, surrounded entirely by smooth polished walls, positively prevents the file serrations from contacting any part of the finger or the finger nail with the exception of the edge of the nail to be trimmed. Thus the instrument, even though power driven at a relatively high rate of speed, is completely and absolutely safe in use to both the operator and the person receiving the manicure. As above noted, the taper of walls 38 and 39 reduces the thickness of the rims 41 and 42, and preferably the thickness of these rims is reduced sufficiently to admit the rim to the underside of the nail, particularly between the nail and its bed at the edge of the nail. In order to remove the sharpness of these rims by reason of their thinness, I prefer to provide the rims with a rounded, bead-like form, as illustrated in Figure 3.

As hereinabove noted, the manicuring instrument of the present invention is designed as a companion instrument to the one disclosed and claimed in my co-pending application Serial No. 33,077. In that application, there is shown a rotary emery disc which is preferably used at the beginning of the manicuring operation to shape

the nail into the general form desired. The emery disc may leave a slight burr along the edge of the nail, and the instrument of the present invention is ideally suited to remove this burr and provide a very finely-cut and finished edge surface for the nail. If desired, the present instrument may be used alone for manicuring the nail, or with other types of instrument for shaping the nail. Preferably, the file teeth 37 are relatively fine in their construction so as to provide the highly-finished edge desired.

To obtain best results from the tool, the head should be driven at a substantially constant speed of rotation and desirably the flexible drive shaft 16 is connected to an electric motor having such a constant speed of rotation within the range of 500 to 2,000 R. P. M. Preferably, several speeds within this range should be available, to enable the operator to select the best speed for trimming and finishing the various finger nails encountered. The diameter of the head corresponding with the indicated speed range is approximately one-fourth to one-half of an inch.

I claim:

- 25 1. A rotary manicuring file comprising, a disc shaped body having substantially flat front and rear sides parallel to each other and perpendicular to the longitudinal axis of said body, a stem extending axially from said rear side and adapted for connection to a rotary drive, said body being formed with a peripheral recess having a flat cylindrical base and a pair of smooth outwardly diverging side walls extending from the front and rear edges of said base, the outer extremities 30 of said side walls joining said front and rear sides of said member in smooth thin annular rims, and file serrations formed in said base, the width of said base between said front and rear edges 35 functioning to confine a fingernail on said serrations without appreciable movement of said nail across said width.
2. A rotary manicuring file comprising, a disc shaped body having substantially flat front and rear sides parallel to each other and perpendicular to the longitudinal axis of said body, a stem 40 extending axially from said rear side and adapted for connection to a rotary drive, said body being formed with a peripheral recess having a flat cylindrical base and a pair of smooth outwardly diverging side walls extending from the front and rear edges of said base, the outer extremities 45 of said side walls joining said front and rear sides of said member in smooth thin annular rims, and a plurality of circumferentially-spaced axially extending file serrations formed in said base, the width of said base between said front and rear edges 50 functioning to confine a fingernail on said serrations without appreciable movement of said nail across said width.
3. A rotary manicuring file comprising, a disc shaped body having substantially flat front and rear sides parallel to each other and perpendicular to the longitudinal axis of said body, a stem 55 extending axially from said rear side and adapted for connection to a rotary drive, said body being formed with a peripheral recess having a flat cylindrical base and a pair of smooth outwardly diverging side walls extending from the front and rear edges of said base, the outer extremities 60 of said side walls joining said front and rear sides of said member in smooth thin annular rims, and a plurality of circumferentially-spaced axially extending file serrations formed in said base, the width of said base between said front and rear edges 65 functioning to confine a fingernail on said serrations without appreciable movement of said nail across said width.
